UNITED STATES PATENT OFFICE.

GEORGE CLOUTTS, OF LOS ANGELES, CALIFORNIA.

GAS-HEATER.

1,247,932.

Specification of Letters Patent.

Patented Nov. 27, 1917.

Application filed November 27, 1916. Serial No. 133,578.

To all whom it may concern:

Be it known that I, GEORGE CLOUTTS, a citizen of the United States, residing at Los Angeles, in the county of Los Angeles, State 5 of California, have invented new and useful Improvements in Gas-Heaters, of which the following is a specification.

This invention relates to heaters; and particularly to heaters of the kind designed to 10 be used in a room to directly heat the atmosphere therein; and more particularly to that class of heaters known as gas heaters, although it will be understood that my heater may be designed to use fuel other than gas. 15 It is an object of this invention to provide a simple heater which will efficiently radiate to the surrounding atmosphere a high percentage of the heat of combustion of the fuel. It is also an object to provide a heater 20 which is easily constructed, manufactured, and assembled, and one in which the various parts are easily accessible. It is also an object, in a heater of the character described, to provide visibility of the heating flame, 25 and at the same time to provide an efficient heat radiating structure surrounding the fire box in which the flame burns.

With these, and other objects in view, as will hereinafter appear, I have provided a 30 heater such as described in the following specification, reference being had to the accompanying drawings in which, for the purpose of this specification, I have illustrated a preferred form of my heater. In these 35 drawings Figure 1 is an elevation of the heater, parts being broken away for purposes of illustration; Fig. 2 is a central vertical longitudinal section of the heater; Fig. 3 is a central vertical cross section of the 40 heater taken as indicated by line 3—3 on Fig. 2; and Fig. 4 is a horizontal section of the heater taken as indicated by line 4—4 on Fig. 2.

In the drawings the numeral 10 designates 45 a suitable base, preferably made of iron, in box-like form, with an inwardly turned flange 11 at its upper side. A fire box 12 is mounted upon this base; the base 10 having air inlet opening 10^a and the fire-box having air inlet opening 12^a, adjacent the burner 13 therein. This burner 13 needs 50 here no particular comment; as any efficient burner will suffice; the burner preferably being elongated in form and preferably embodying two burner tubes such as illustrated. The combustion chamber or fire-box 12 has

a vertically extending baffle wall 14 which extends from the rear side of the bottom of the fire box to a point near the top; so that the heated gases may travel upwardly and over the top of the baffle wall and then downwardly to the outlet 15. This outlet 15 connects with the lowermost convolution 16 of the heat radiating tube which surrounds the fire box as illustrated. This lowermost convolution rests upon the flange 11 of the base box 10; and, from the point of communication with the opening 15, this lowermost convolution extends in opposite directions around the fire box 12 to points at the front 70 of the fire box. The fire box has a front door opening and a door 20 with a transparent panel 21; the door being hinged at 22 and having fastening means at 23. I provide a front plate 24; which front plate 75 may be decorated in any suitable manner to give a suitable appearance to the heater; and this front plate has an opening 25 opposite the door opening of the fire box. The convolution 16 proceeds to points at opposite 80 sides of this opening 25, and behind front plate 24; and connecting members 26 are provided for connecting the ends of the tubes at these points with communicating boxes 27. The next convolution 30 of the radiating tube also connects into these boxes, by 85 connecting members 26^a. The gases which enter the convolution 16 at the point 15, travel to the sides and forwardly around the fire box 12 to the boxes 27 and thence upwardly into the next convolution 30. This convolution 30 is connected at 31 with the next convolution 32; and in this convolution 32 the gases pass around from the point 31 in a complete circuit and thence through the 90 connection 33 to the next convolution 34, through which they pass in a complete circuit, until they arrive at the discharge opening 35, whence they pass to any suitable discharge flue. Of course, there may be as 95 many convolutions of the tube as desired; but I find, in actual practice, that the number of convolutions illustrated is sufficient to cause efficient radiation of the heat to the surrounding atmosphere; the radiation being so efficient that the outlet 35 is only warm and not at all hot.

I provide a top 40 for the heater, this top having an opening 41 covered by a register cover 42 of any suitable or usual design. 110 This opening 41, and register cover 42, substantially correspond in size to the space in-

closed within the convolutions of the radiating tube; so as to afford an opening for the free upward movement of the heated air which rises in the space within the radiating tube and surrounding the fire box 12.

It will be noted that the radiating tube is spaced from and around the fire box 12, and that the superimposed convolutions are spaced from each other, so as to allow free access of the surrounding atmosphere to the space between the convolutions and the fire box. The heated fire box heats the surrounding air by conduction; this air moves upwardly and in doing so draws cold air in between the convolutions of the tube, drawing the cold air over the hot tubes. The air is then first heated by conduction from the tubes and then further heated by conduction from the hot fire box, acquiring a maximum temperature before leaving the heater. The base of the heater is preferably provided only with sufficient holes to allow entry of enough air for combustion purposes in the fire box; or at least the holes in the base are so restricted that the upward air current around the fire box draws air horizontally between the convolutions rather than merely drawing it up from the bottom of the heater. In this manner the air is moved over practically the whole surface of the tube, causing efficient conduction from the tube to the moving air. This air is drawn in horizontally from all sides; from the surrounding atmosphere, by the action of the draft forced by the upward air motion around the fire box, and flows equally through all the spaces between the tube convolutions. The convolutions are held in their spaced relation, and the different parts of the heater are held together in the manner now described. Vertical rods 45 extend through the structure, being secured to the base 10 below, and being secured to brackets 46 above, which brackets are secured to the top 40. These rods 45 extend through each of the convolutions of the radiating tube; and spacing washers or the like 46 are provided between the adjacent convolutions so as to hold the convolutions in their proper spaced relation. It will be seen that these rods afford means for easy assembly of the different parts of the heater, and that they hold the parts rigidly in form and place.

From the foregoing description it will be seen that the radiating tubes are freely exposed to the surrounding atmosphere; that the surrounding atmosphere is freely admitted to the space between the tubes and the fire box, and that free upward circulation of the heated air is allowed. This results in efficient conduction and radiation of the heat directly to the circulating atmosphere. And, in this connection, I call attention to a distinctive feature of my

heater; it delivers heat directly to the open air rather than to an inclosed body of air, as is the case in a hot air furnace. The surrounding cold atmosphere is drawn into close contact with the heated tube, drawn over and between the convolutions, and is first heated there. Then it passes to the interior space directly around the fire box and is there further heated. The whole action is that of a natural movement or forced draft of air caused by the upward movement of the heated air. It will be noted that the base 10, as hereinbefore stated, is so situated as to prevent the entry of air from below directly upwardly into the space between the fire box and the convolutions of the radiating tube. This forces the air to be drawn in horizontally over and between the convolutions of the tube, causing the cold exterior air to be drawn over all of the tube surface; rather than allowing a mere rush of air directly upwardly through the space, as would be the case if the air were not prevented from entering below. And it is this particular feature of my device to which I direct the following claims. It will be noted that I have described a preferred form of my device with some particularity; but I do not thereby limit my invention to the specific details described, as these details may be modified and varied within the scope of the claims.

Having described a preferred form of my invention, I claim:

1. An open air heater, embodying an inner fire box having a vertical baffle over the top of which the heated gases may flow, a burner in the lower part of the fire box, the fire box having air inlet openings adjacent the burner and an outlet near its bottom behind the baffle, a heat radiating tube coiled in horizontal convolutions around the fire box, the lower end of the tube communicating with the fire box outlet; the convolutions of the tube being freely exposed to the surrounding atmosphere, and being vertically spaced from each other and horizontally spaced from and around the fire box so as to allow free natural circulation of air between and around the tubes and between them and the fire box, said fire box having a door opening and door, and an exterior front plate outside the tube convolutions having an opening therethrough opposite the fire box door, the lowermost tube convolution extending from the back around opposite sides of the fire box to points at opposite sides of the front plate opening, communicating means at said points between the lowermost convolution and the next one above, a base upon which the fire box and the tube convolutions are mounted, vertical securing rods secured to the base and top and pass-

ing through the several tube convolutions, and spacers on the rods to space the several convolutions apart.

2. In an open air heater, an inner fire box 5 with a door opening at one side, a radiating tube coiled about the fire box leaving an open space in front of the door opening, and lateral connections between adjacent convolutions of the tube at the sides of said 10 open space.

3. In an open air heater, an inner fire box with a door opening at one side, a radiating tube coiled about the fire box in

horizontal convolutions, those convolutions which are opposite the door-opening terminating at opposite sides of the opening, and lateral vertical connections between the ends of adjacent convolutions at the opposite sides of the door opening. 15

In witness that I claim the foregoing I 20 have hereunto subscribed my name this 18th day of November 1916.

GEORGE CLOTTTS.
